(57) **CLAIM**

The ornamental design for a strap assembly for a bucket, as shown and described.

DESCRIPTION

FIG. 1 is a top perspective view of a strap assembly for a bucket, showing the strap assembly coupled to a bucket; FIG. 2 is a bottom perspective view of the strap assembly for a bucket of FIG. 1;

FIG. 3 is a bottom plan view of the strap assembly for a bucket of FIG. 1;

FIG. 4 is a top plan view of the strap assembly for a bucket of FIG. 1;

FIG. 5 is a front elevational view of the strap assembly for a bucket of FIG. 1;

FIG. 6 is a rear elevational view of the strap assembly for a bucket of FIG. 1;

FIG. 7 is a right-side elevational view of the strap assembly for a bucket of FIG. 1; and,

FIG. 8 is a right-side elevational view of the strap assembly for a bucket of FIG. 1.

The broken away symbols in the drawings indicate that any portion of the article beyond what is shown forms no part of the claimed design.

1 Claim, 4 Drawing Sheets
